UNITED STATES PATENT OFFICE.

DANA H. BENJAMIN, OF CLEVELAND HEIGHTS, OHIO, ASSIGNOR TO THE AMERICAN LAUNDRY MACHINERY COMPANY, OF CINCINNATI, OHIO, A CORPORATION OF OHIO.

PRESSING-MACHINE.

1,327,976.

Specification of Letters Patent. Patented Jan. 13, 1920.

Application filed March 12, 1917. Serial No. 154,211.

To all whom it may concern:

Be it known that I, DANA H. BENJAMIN, citizen of the United States, residing at Cleveland Heights, in the county of Cuyahoga and State of Ohio, have invented certain new and useful Improvements in Pressing-Machines, of which the following is a specification.

This invention relates to pressing machines, and more particularly to what are known as sleeve stickers. Machines of this kind are used for ironing and thereby sticking together the sleeves of laundried shirts, to do away with the insertion of pins and 15 yet hold the cuffs in the desired curved flaring form.

The object of the invention is to provide a simple form of machine for ironing shirt sleeves, which can be readily operated; whose 20 output is large as compared with prior machines for this purpose; which will take care of either sleeve and give a proper finish to the sleeve facing; and which embodies guiding and holding means for the sleeve so 25 that a uniform product with a superior finish and appearance may be obtained.

Further objects of the invention are in part obvious and in part will appear more in detail hereinafter.

30 The invention comprises the pressing machine hereinafter described and claimed.

In the drawings, which represent one embodiment of the invention, Figure 1 is a side elevation; and Fig. 2 is a front view, 35 on a larger scale, showing a sleeve in position to be pressed.

The machine shown in the drawings comprises a suitable frame having a base 1 in the form of a hollow column provided with 40 two spaced platforms 2 to which are rigidly secured the feet 3 of a curved upper frame member 4 whose arched upper portion 5 supports a stationary pressing or ironing member 6, preferably heated by a supply of steam 45 or other heating medium delivered thereto by pipe 7. Base 1 is provided with suitable guides for a vertically slideable rod 8 having a suitable screw adjusting device 9 to vary 50 its effective length. Said rod, at its upper end, supports the movable pressing member 10, which may also be heated by steam introduced to its inner chamber through pipe 11.

Any suitable means may be provided for reciprocating the movable pressing member 55 to produce coöoperating pressing movement

between the pressing members. As illustrated rod 8 is jointed at its lower end to the upper link 12 of a pair of toggle links, the lower link 13 of which is one arm of a bell crank lever whose other arm 14 is formed as 60 a foot treadle.

By pressing down on the foot treadle the lower member is elevated into pressing relation with the upper member and pressure is applied to iron a sleeve lying between said 65 members. When the foot treadle is released the lower pressing member drops by gravity and may be cushioned to prevent shock by springs or other devices (not shown) as will be obvious.

70 Either or both of the pressing members may be provided with suitable padding, and the drawings show the upper or stationary member as having a plain metal ironing surface coöoperating with the padding 15 of the 75 lower member.

Suitable means is also provided for guiding the sleeve to be ironed to its place and for assisting the operator in holding said sleeve while ironing the same. For this purpose a thin metal plate 16 is located at one side of the pressing members, said plate lying in a vertical plane and having a narrow slot 17 with one end open at the front of the machine, the opposite end of said slot being 80 closed and serving as an abutment for a purpose which will appear hereinafter.

If both pressing members are movable, as they may be, said slot will be located opposite the place where the pressing members 90 come together, but as one member is stationary in the machine shown the plate is so located that the slot lies parallel with the edge of the stationary pressing member and just below its lower pressing face. Said plate 95 may be attached to any suitable support, such as the main frame, but is shown as rigidly connected by bolts or screws 18 to the upper pressing member.

In using the machine the operator slips 100 the sleeve into the slot with the cuff protruding beyond the guide plate, as shown in Fig. 2 until one edge of the sleeve abuts the closed end of the slot 17, which locates the sleeve in proper position to be pressed. The facing along one edge of the sleeve slit is held uppermost so as to be pressed against the plain ironing surface of the upper member. The sleeve is pulled or stretched lengthwise to remove wrinkles and folds, the thick plies 110

of the cuff preventing it from being drawn through slot 17. The plate, however, enables all of the sleeve body to be pulled into position between the pressing members and insures pressing the sleeve uniformly up to a point close to the cuff.

Preferably the machine is arranged for pressing either right or left sleeves. As the facing strips on the two sleeves are on opposite edges of the sleeve slit it is therefore convenient to use two plates 16 located on opposite sides of the pressing members, one plate for receiving the cuff of one sleeve and the other plate the cuff of the other sleeve. Both plates are of course detachable from their supports to enable the padding on the pressing members to be readily applied or removed, as desired.

The machine described is of simple form and enables the sleeves to be ironed rapidly and with uniform excellence of finish and always forms and preserves the curved flare of the cuff most desired.

What I claim is:—

1. A sleeve sticker, comprising relatively movable pressing members having coöperat-

ing pressing surfaces, and a sleeve guiding member provided with a narrow slot lying opposite the space between said pressing members, said slot being open at one end and closed at the other to form a sleeve locating abutment.

2. A sleeve sticker, comprising coöperating relatively movable pressing members, and sleeve guiding and supporting means having a narrow slot at one side of one of said members for a left sleeve and a narrow slot at the other side of said member for a right sleeve.

3. A sleeve sticker, comprising coöperating relatively movable pressing members, and sleeve guiding and supporting means having a narrow slot at one side of one of said members for a left sleeve and a narrow slot at the other side of said member for a right sleeve, said slots being open at one end for introducing the sleeve thereinto and closed at the other end to form abutments for locating the sleeve relative to the pressing area.

In testimony whereof I affix my signature.

DANA H. BENJAMIN.
